SHAVING OR HAIR CLIPPING APPARATUS

Ralph E. Jones, Grand Rapids, Mich.

Application January 17, 1940, Serial No. 314,287

16 Claims. (Cl. 30—43)

This invention relates to improvements in shaving or hair clipping apparatus.

This is a continuation in part of my copending application Serial No. 162,575, filed September 7, 1937, which matured into Letters Patent No. 2,203,021 of June 4, 1940, and also relates to improvements in the hair clipping and shaving devices illustrated in my copending applications Serial No. 53,809, filed December 10, 1935, and Serial No. 134,439, filed April 1, 1937, which matured into Letters Patent No. 2,228,768 of January 14, 1941, and No. 2,203,020 of June 4, 1940, respectively.

The main objects of this invention are:

First, to provide an improved electrically actuated mechanical shaving or hair clipping device wherein the cutting head and cutter therein may be readily assembled for use and disassembled for cleaning.

Second, to provide a device of the type described having a removable head which is firmly held in operative position by a single retaining element.

Third, to provide a device of the character described, wherein the head and cutter slidable therein may be removed from the handle and likewise separated from each other for most effective cleaning or sterilizing thereof and replaced in operative relation with a minimum of time and manipulation, there being no possibility of assembling them in other than the proper operative relation.

Further objects relating to details and economies of my invention will definitely appear from the description to follow. The invention is defined in the claims.

A structure embodying the features of my invention is illustrated in the accompanying drawing, wherein:

Fig. 1 is a view in side elevation illustrating an electrically actuated mechanical shaving or hair clipping device which is provided with the improvements of my invention, illustrating details of construction involved in those improvements.

Fig. 2 is an enlarged fragmentary view in vertical longitudinal section through the head portion of the device illustrated in Fig. 1 and in section on line 2—2 of Fig. 3.

Fig. 3 is a fragmentary view in section on line 3—3 of Figs. 1 and 2.

Fig. 4 is a perspective view illustrating the securing or locking pin constituting an element of the assembly of my invention.

Fig. 5 is an exploded or separated view illus-

trating the manner in which the structure of my invention is disassembled for cleaning and the like.

Fig. 6 is a fragmentary view in longitudinal vertical section illustrating a modified form of cutter head in accordance with my invention.

Referring to Fig. 1, the reference numeral 1 indicates an electrically actuated mechanical shaving or hair clipping device having a handle

2. This handle is of suitable size for gripping and houses an electric actuating motor as is the common practice in devices of this type. The handle has at its outer end a channel-like recess 3 (see Fig. 3) removably receiving the cutter head 4. This head is provided with a channel-like chamber 5 receiving and housing the cutter 6 for reciprocal movement of the latter therein. The head is provided with openings 7 adapted to be aligned with corresponding openings 8 in the handle through which rods 9 project to engage sockets 10 in the cutter. The cutter is driven by the electric motor (not shown) in a conventional manner for reciprocation in the head 4.

At each side, the head 4 has a curved portion 11 merging into a cutting face 12 which has transverse slots 13 therein extending into the curved portions. These slots provide a series of transverse combined guard and shear bars 14 which coat with spaced cutter members 15 on cutter 6, the cutter members and shear bars being in sliding relation to effect a shearing action in a manner well known to the art.

In accordance with my invention, I provide

35 end or guard members 16, 17 for the cutter head 6, which are of channel section, preferably sheet metal stampings. These end members have curved side portions and end portions 18 complementing the curved side portions 11 of the

40 head and merging into the curved side portions 11 of the head, also merging into the flat top of the latter. The end members are associated with the head in a manner to be described, so

45 that this merging relation of the curved surfaces is possible, with the result that a cutting head having smoothly rounded sides and ends results, permitting the same to be pressed very firmly against the skin without resulting in digging into or abrasion thereof, and on the whole

50 greatly improving the cutting action.

As illustrated in Fig. 2, the end members or guards 16, 17 are secured in operative relation to the razor structure in somewhat different manners. That is, the guard 16 is substantially longer than the guard 17 and terminates in an

outwardly angled base or shank portion 19 which is received in a correspondingly shaped recess in handle 2, being secured to the handle by a screw 20. On the other hand, the guard 17 is secured directly to one end of the cutter head 4 by means of a screw 21.

In order to secure the cutter head 4 to handle 2 in the channel 3 of the latter, I utilize a tapered securing pin 22 which is illustrated per se in Fig. 4 and also in its coactive relation to the other parts in Figs. 2 and 3. This pin is tapered from end to end and has a pair of parallel flat sides which enable the same to be non-rotatably engaged with aligned holes 23 (of similar flat sided configuration, but of different size) in the handle at opposite sides of the channel-like recess 3. The head has a circular hole 24 extending therethrough and adapted to likewise receive pin 22 to pin the head securely to the handle. It will be noted that hole 24 is reduced in diameter approximately midway of the same to provide a shoulder 25 against which the pin engages to exert wedging retaining force on the head. By reason of the fact that the openings 23 have the flat sides thereof inclined upwardly and to the right as clearly illustrated in Fig. 5, the tapered securing pin 22 urges the head 4 downwards and also to the left, thereby effectively securing the same in proper position on the bottom of the channel and snugly against the left guards 16 on the handle. The holes or openings 23, being of different size, render it impossible to successfully insert pin 22 from the wrong direction and provide that the upward force of reaction will be effectively taken by the handle at both sides of the head receiving channel therein. This provides an effective clamping action and at the same time the pin slips very freely into and out of position.

In order to retain the pin in position, I provide a turn button or clip 26 (see Fig. 1) which is pivoted at 27 to be swung into and out of engagement with a keeper 28. The clip has a seat 29 which snaps over the end of pin 22 to urge the same in its direction of engagement, as illustrated in Fig. 3.

The foregoing details of construction enable several decided advantages to be attained. In the first place, in operative relation, the cutter head is secured in snug displacement-resisting engagement with the handle in its proper position against the left-hand guard 16. In the second place, with the guard 16 secured to the handle and the guard 17 attached to the head, it is possible to remove the head and cutter in the manner illustrated in Fig. 5 without disturbing guard 16. This permits the cutter to be readily withdrawn from within the head for cleaning or sterilizing and just as readily replaced in operative position for use. The tapered pin securing means automatically effects the proper engagement of the head with the guard 16 on the handle. There is a minimum of parts to be manipulated in the aforesaid taking down and replacement and the whole assembly is a very inexpensive one.

Inasmuch as removal of the guard member 17 from the head 4 is unnecessary, it may be integrally and non-removably secured thereto, as illustrated in the modified embodiment of Fig. 6, wherein the guard designated 30 is spotwelded to the base 31 of the cutter head at 32 and also at the point 33. It might even be practical to cast these parts integrally or at least to produce

all of the parts of the head save its base as a sheet metal stamping.

I have illustrated and described my improvements in embodiments which are very practical.

5 I have not attempted to illustrate or describe other embodiments or adaptations as it is believed this disclosure will enable those skilled in the art to embody or adapt my improvements as may be desired.

10 Having thus described my invention, what I claim as new and desire to secure by Letters Patent is:

1. In a shaving apparatus of the class described, the combination of a handle, an open ended head adapted to be removably secured to said handle and to slidably receive a cutter interiorly of the head, said head having a flat cutting face, said head having rounded side portions merging into said face, and guard elements 15 at either end of the head having rounded side and end portions merging into said face and said rounded head portions, one of said guard elements being fixedly secured to said handle in operating relation to the head and the other thereof being fixedly secured to the head in operative relation thereto, and means for removably attaching said head to the handle comprising a tapered pin having two flat sides parallel to one another, said head and handle having holes extending therethrough adapted to receive said pin for wedging engagement thereby and certain of said holes having flat sides for guiding said pin disposed angularly relative to the axis of the handle whereby the pin exerts longitudinal and lateral force components tending to urge the head against the guard on said handle.

2. In a shaving apparatus of the class described, the combination of a handle, an open ended head adapted to be removably secured to said handle and to slidably receive a cutter interiorly of the head, said head having a flat cutting face, said head having rounded side portions merging into said face, and guard elements 40 at either end of the head having rounded side and end portions merging into said face and said rounded head portions, one of said guard elements being fixedly secured to said handle in operating relation to the head and the other thereof being fixedly secured to the head in operative relation thereto, and means for removably attaching said head to the handle comprising a tapered pin, said head and handle having holes extending therethrough adapted to receive said pin for wedging engagement thereby.

3. In a shaving apparatus of the class described, the combination of a handle, an open ended head adapted to be removably secured to said handle and to slidably receive a cutter interiorly of the head, said head having a flat cutting face, said head having rounded side portions merging into said face, and guard elements 45 at either end of the head having rounded side and end portions merging into said face and said rounded head portions, one of said guard elements being fixedly secured to said handle in operating relation to the head and the other thereof being fixedly secured to the head in operative relation thereto, and means for removably attaching said head to the handle comprising a tapered pin, said head and handle having holes extending therethrough adapted to receive said pin for wedging engagement thereby.

4. In a shaving apparatus of the class described including a handle and an open ended head adapted to be removably secured to said handle and to slidably receive a cutter interiorly of the head, guard elements at either end of the

head, one of said guard elements being fixedly secured to said handle in operative covering relation to one end of the head and the other thereof being fixedly secured to the head in operative covering relation to the other end thereof, and means for removably attaching said head to the handle comprising a tapered pin having two flat sides parallel to one another, said head and handle having holes extending therethrough adapted to receive said pin for wedging engagement thereby and certain of said holes having flat sides for guiding said pin disposed angularly whereby the pin exerts longitudinal and lateral force components tending to urge the head against the guard on said handle.

5. In a shaving apparatus of the class described including a handle and an open ended head adapted to be removably secured to said handle and to slidably receive a cutter interiorly of the head, guard elements at either end of the head, one of said guard elements being fixedly secured to said handle in operative covering relation to one end of the head and the other thereof being fixedly secured to the head in operative covering relation to the other end thereof for removal as a unit therewith from the handle, and means for removably attaching said head to the handle comprising a tapered pin, said head and handle having holes extending therethrough adapted to receive said pin for wedging engagement thereby.

6. In a shaving apparatus of the class described including a handle and an open ended head adapted to be removably secured to said handle and to slidably receive a cutter interiorly of the head, guard elements at either end of the head, one of said guard elements being fixedly secured to said handle in operative covering relation to one end of the head and the other thereof being fixedly secured to the head in operative covering relation to the other end thereof for removal as a unit therewith from the handle, and means for removably attaching said head to the handle.

7. In a shaving device having a handle, an open ended cutting head adapted to be removably attached to the handle, and a cutter slidably received by the head, a pair of generally similar guard elements having rounded side and end surfaces merging into the sides of said head and into the cutting surface of the latter, one of said guard elements being fixedly secured to said handle and the other thereof being fixedly secured to said head whereby to be removable from the handle therewith, and means for removably attaching said head to the handle, comprising a tapered flat sided pin extending transversely of the head and handle, and aligned recesses in said head and handle for wedgingly receiving said pin, at least one of said recesses being flat sided and inclined to the axis of the handle for receiving and guiding said pin whereby the latter exerts lateral and longitudinal components of wedging force serving to urge the head into engagement with the handle and handle guard member.

8. In a shaving device having a handle, and an open ended cutting head adapted to be removably attached to the handle, a pair of guard elements, one of said guard elements being fixedly secured to said handle and the other thereof being fixedly secured to said head whereby to be removable from the handle therewith, and means for removably attaching said head to the handle, comprising a flat sided wedge shaped pin extending transversely of the head and handle, and

aligned recesses in said head and handle each in frictional engagement with a wedge surface of the pin and wedgingly receiving the same, at least one of said recesses being flat sided and inclined to the axis of the handle for engaging and guiding the flat side of said pin whereby the latter exerts lateral and longitudinal components of wedging force serving to urge the head into engagement with the handle and handle guard member.

9. In a shaving device having a handle, an open ended cutting head adapted to be removably attached to the handle, and a cutter slidably received by the head, a pair of generally similar guard elements having rounded side and end surfaces merging into the sides of said head and into the cutting surface of the latter, one of said guard elements being fixedly secured to said handle and the other thereof being fixedly secured to said head whereby to be removable therewith as a unit from the handle, and means for removably attaching said head to the handle, comprising a tapered pin extending transversely of the head and handle, and aligned recesses in said head and handle for wedgingly receiving said pin to urge the head into engagement with the handle and handle guard member.

10. In a shaving device having a handle, an open ended cutting head adapted to be removably attached to the handle, and a cutter slidably received by the head, a pair of generally similar guard elements having rounded side and end surfaces merging into the sides of said head and into the cutting surface of the latter, one of said guard elements being fixedly secured to said handle and the other thereof being fixedly secured to said head whereby to be removable therewith as a unit from the handle, and means for removably attaching said head to the handle.

11. In a shaving device of the type described having a handle and an open ended head adapted to be detachably secured thereto, an end guard element for one end of said head fixedly secured to said handle, a further end guard element fixedly secured to the other end of said head and detachable therewith as a unit from the handle, a tapered pin extending transversely of the head and handle, said head and handle having aligned openings receiving and wedgingly engaging the tapered pin at either side of a vertical plane through the axis thereof whereby to exert lateral and longitudinal components of wedging force thereon with reference to the axis of the handle, and means for retaining the pin in place.

12. In a shaving device of the type described having a handle and an open ended head adapted to be detachably secured thereto, an end guard element for one end of said head fixedly secured to the handle, a further guard element fixedly secured to the other end of said head and detachable therewith as a unit from the handle, and means for attaching said head to the handle.

13. In a shaving device of the type described having a handle provided with a channel-like recess at the outer end thereof, a head adapted to be detachably secured in said recess to project therefrom, said head having an opening at one end thereof to permit the introduction and removal therefrom of a cutter, a guard secured to said handle and adapted to close the said end opening of said head when the head is in position on the handle, the other end of the head being closed by means independent of the handle and removable with the head from the handle

as a unit, and means for clampingly securing said head within said recess and acting to urge the same against said guard when the head is in assembled position.

14. In a shaving device of the type described having a handle provided with a channel-like recess at the outer end thereof, a head adapted to be detachably secured in said recess to project therefrom, said head having an opening at one end thereof to permit the introduction and removal therefrom of a cutter, a guard secured to said handle and adapted to close the said end opening of said head when the head is in position on the handle, the other end of the head being closed by means independent of the handle and removable with the head from the handle as a unit, and means for securing said head within said recess.

15. In a shaving device of the type described having a handle, a head adapted to be detachably secured to said handle, said head having an opening at one end thereof to permit the introduction and removal therefrom of a cutter, a guard secured to said handle and adapted to

close the said end opening of said head when the head is in position on the handle, the other end of said head being closed by means secured thereto and independent of the handle whereby

5 to be removed with the head from the handle as a unit, and means for clampingly securing said head to said handle and acting to urge the same toward said guard when the head is in assembled position.

16. In a shaving device of the type described having a handle, a head adapted to be detachably secured to said handle, said head having an opening at one end thereof to permit the introduction and removal therefrom of a cutter, a guard secured to said handle and adapted to close the said end opening of said head when the head is in position on the handle, the other end of said head being closed by means secured thereto and independent of the handle whereby to be removed with the head from the handle as a unit, and means for securing said head to said handle with said guard in operative closing relation to said first named head opening.

RALPH E. JONES.
